CLAIM

The ornamental design for a cooking appliance as shown and described.

DESCRIPTION

This application is also related to U.S. patent application Ser. No. 29/967,337, filed Oct. 9, 2024, entitled Cooking System, the entire disclosure of which is hereby incorporated herein by reference.

FIG. 1 is a perspective view of a cooking appliance showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions of the cooking appliance shown in broken lines in FIGS. 1-7 illustrate unclaimed portions of the cooking appliance and form no part of the claimed design.

The surface shadings and contour lines shown in FIGS. 1-7 represent the three-dimensional character and contour of the cooking appliance, and are not intended to limit the cooking appliance to any particular materials, colors, or surface decorations.
